[57] ABSTRACT

The specific feature of the device lies in that its driving discs linked kinematically with the marking drums are installed on a reversibly-rotatable shaft with the aid of springs and each disc is provided with a system of retainers whose number and position correspond to the number and position of the marking signs, each disc carrying a stop which can interact with the retainer; this ensures rapid and simultaneous remote changing of the position of the marking drums; besides, the device incorporates a system of drive links installed on the shaft, and stops located on the discs; these drive links and stops allow the marking drums to be returned rapidly and remotely to the initial position.

MARKING DEVICE

The present invention relates to the marking devices and, particularly, those intended for marking large-size products.

In the process of marking, the product is marked with figures, letters and signs used separately or, most frequently, in combination with one another.

The products being marked vary widely with respect to their material and shape; thus they may be metal products, such as plates, large rolled sections, pipes, etc. or wooden products in the form of shields, panels, etc.

Known in the art are marking devices with remote changing of the marks.

Of these, most common are the punch-marking devices comprising a system of marking discs or drums whose cylindrical surface is provided with the marks to be applied to the surface of the product. Each of these discs or drums is connected by an endless chain with a sprocket rotated by an individual pneumatic or hydraulic drive.

On each operation of the drive the sprocket turns one step; accordingly, the marking disc or drum also turns one step thus changing the mark.

By turning each sprocket through a required angle, the marking discs or drums are set to the necessary positions, thus selecting the required set of figures, letters or signs.

A disadvantage of the known devices lies in that each sprocket is turned through the required angle for selecting the desired mark by engaging its drive many times. As a result, the setting of the marking drums or discs becomes complicated and time-wasting while the device proper is bulky and heavy.

Also known in the art are other marking devices consisting of a casing provided with a port which is located at the bottom part of said casing and faces the product; installed inside the casing, along said port, are a number of nozzles covered by shutters which have through holes in the shape of the marks. The casing is mounted on a trolley which moves along a jib, the latter being installed across a roller bed which carries the continuously moving products to be marked.

A disadvantage of these devices lies in the complicated control of the shutters and in the difficulties of changing their position quickly, including their shifting to the initial position. The use of these devices renders the marking process difficult and time-wasting.

Besides, still other devices are known for marking the continuously moving products, e.g., metal strip or steel sections. These devices comprise a marking drum or wheel whose cylindrical surface is provided with the marking signs. The disadvantages of these devices include the impossibility of changing the set of the marking signs in the process of marking and changing them at a distance.

An object of the invention resides in eliminating the disadvantages of the above-described marking devices.

The invention aims at providing a device with such a system of retainers which would ensure rapid and individual fixing of the drums in the required position.

This object is achieved by providing a marking device which comprises marking drums connected, each, with the driving disc by an endless flexible link in which, according to the invention, the driving discs are secured on a reversibly-rotatable shaft by means of springs and

each disc has a system of retainers located along the entire cylindrical surface of said disc, the number and positions of these retainers corresponding to the number and position of the signs on the marking drum; each disc is fitted with a stop interacting with the retainers intended for this particular disc; besides, each disc has one more stop and the shaft carries drive links whose number corresponds to the number of the discs, said drive links interacting with the last-mentioned stops during reverse rotation of the shaft.

To ensure remote and automatic setting of the marking drums, the retainers are of the electromagnetic type, connected electrically with the control system of the device.

Now the device will be described in detail by way of example with reference to the accompanying drawings, in which:

FIG. I is a longitudinal vertical section of the marking device according to the invention;

FIG. 2 shows the same device, a section taken along line II-II in FIG. I.

The device comprises a casing I (FIGS. I, 2) accommodating marking drums 3 installed between rollers 2 (FIG. 2), and driving discs 6 installed on a common shaft 4 with the aid of springs 5 (FIG. I).

The shaft 4 is driven by a reversible electric motor 7. Each drum 3 is connected with the disc 6 by an endless cable 8 (FIGS. I and 2).

Each marking drum 3 is made in the form of a hollow cylinder and has cutouts 8a in the form of figures, letters or other signs, spaced at equal distances along the entire cylindrical surface.

Arranged along the entire cylindrical surface of each disc 6 are electromagnetic retainers 9 which are secured rigidly to the intermediate walls 10 of the casing I.

Each retainer corresponds to a certain sign on the marking drum 3 of the corresponding disc 6. Each electromagnetic retainer 9 is connected electrically with the control system (not shown in the drawings).

The rim of each disc 6 is provided with a stop II which can interact with any retainer 9 of one and the same disc 6.

Installed on the shaft 4 are drive links I2 whose number is equal to that of the discs 6. A stop I3 secured in the face of each disc can interact with the drive link I2 during rotation of the shaft 4.

A pipe I4 passing through the drums is fastened to the wall of the casing I. This pipe I4 carries nozzles I5 for the delivery of paint, varnish, etc. Paint and compressed air is supplied to the nozzles through pipes I6 and I7.

The device can be used for stationary work, being mounted on supports. In this case the product I8 to be marked is fed under the drums 3. The device can also be installed on a trolley, a jib, etc. In this case the device moves relative to the stationary product I8. In the course of marking the product should be held at a short distance from the marking drums 3.

The device is operated at a distance, from a central desk provided with a system of buttons or keys.

Such a version is convenient when frequent changes of the marking signs are required.

The device can also be controlled with the aid of a telephone dial with a system of step-by-step selectors.

If the product is marked by ordinal numbers, the control programming mechanism can be either an electro-

mechanical relay or a counting relay of the step-by-step selector type, provided with a device for transferring tens to the next digits. The command pulses are sent separately for each digit through individual channels.

The required set of signs is selected by pressing the buttons or rotating the telephone dial on the control desk. This puts into motion the retainers 9 corresponding to the selected signs. The cores I9 of these retainers 9 move towards the discs 3.

Then the electric motor 7 is started and begins rotating the shaft 4 via the speed reducer 20 (FIG.1). The shaft rotates the discs 6 and, together with them, the drums 3. Each disc continues rotating until its stop II comes to the extended core I9 of the corresponding retainer 9.

After one or more discs have stopped, the remaining discs continue rotating because the discs 6 are fastened on the shaft 4 with the aid of springs 5 which, after the stopping of the discs, begin to be twisted, rotating together with the shaft 4 to which one end of said springs 5 is secured.

The marking drums 3 rotate in correspondence with the rotation of the discs 6, thus being set to the required position.

After the shaft 4 has turned through a required angle 25 the cam 21 operates the transmitter 22 showing the position of the shaft 4; this transmitter sends a signal for stopping the electric motor 7. For visual control and observation of the drum setting, the casing I of the device is provided with a port 23 (FIG.2) through which it is possible to observe the marks on the cylindrical surface of the discs 6. The position of these marks corresponds to the number and position of the marks on the cylindrical surface of the marking drums 3.

Having ascertained that the marking drums 3 are set 35 as required, turn on all the nozzles 15 simultaneously

and mark the product with a spray of pulverized paint or varnish through the cutouts 8a in the drums 3.

Then the electric motor is reversed and the shaft 4 starts rotating in the opposite direction. The drive links 5 I2 act on the stops I3 and return the discs 6 to the initial position. During reverse rotation of the shaft the spiral springs 5 are untwisted. The shaft 4 stops rotating when the cam 21 interacts with the second shaft-position transmitter (not shown in the drawings). After all the 10 discs 6 and, correspondingly, drums 3 have returned to their initial position, all the electromagnetic retainers 9 are deenergized simultaneously and their cores I9 are pulled by the springs into the retainer bodies. In this position the device is ready for the next selection of marking signs and for marking the product.

What is claimed is:

I. A marking device comprising: marking drums; driving discs installed on a common reversibly-rotatable shaft; springs which secure said discs on said shaft; endless flexible cables connecting said marking drums with the corresponding discs; a system of retainers for each of said driving discs; said retainers are located along the entire cylindrical surface of each of said discs and their number and position correspond to the number and position of the signs on each of said marking drums; a stop on each of said discs which can interact with any retainer of the corresponding disc; one more stop on each of said discs; drive links on said shaft, said drive links acting on the last-mentioned stops during the reverse rotation of said shaft, thus returning said discs to the initial position.

2. A device according to claim I, wherein said retainers are of the electromagnetic type connected electrically with the control system of the device.
